UNITED STATES PATENT OFFICE.

EDWARD J. DOBERSTEIN, OF BLUE ISLAND, ILLINOIS, ASSIGNOR TO GOODMAN MANUFACTURING COMPANY, OF CHICAGO, ILLINOIS, A CORPORATION OF ILLINOIS.

MINING MACHINE.

Application filed November 8, 1923. Serial No. 673,426.

To all whom it may concern:

Be it known that I, EDWARD J. DOBERSTEIN, a citizen of the United States, residing at Blue Island, in the county of Cook 5 and State of Illinois, have invented a new and useful Improvement in Mining Machines, of which the following is a specification.

This invention relates to improvements in kerf cutting mining machines and has for its principal object to provide a new and improved device of this description, capable of being easily and quickly handled during its cutting operation and during its movement from place to place.

In carrying out my invention I provide a power driven kerf cutting element permanently supported on a wheel truck, preferably for movement on the mine track. 20 The cutting element is mounted on a pivotal turntable so that it may be supported to swing angularly on both sides of the truck to cut a kerf in advance of the machine. Means are further provided for raising and 25 lowering the cutting element and turntable to various elevations with respect to the truck so as to cut at various heights.

More particularly, the object of the present invention is to provide an improved arrangement of turntable and elevating mechanism whereby the cutting mechanism may be lowered to require a minimum overall height of the apparatus while being moved from place to place in the mine, and further to provide maximum rigidity between 30 the cutting element and the truck.

The invention may best be understood by reference to the accompanying drawings in which:

40 Figure 1 is a central longitudinal section of a mechanism constructed in accordance with my invention, but with the cutting element shown in side elevation. In this view the elevating mechanism and cutting element are shown in full lines in their lowermost position, and in dotted lines in their raised position.

45 Figure 2 is a plan view of the truck with the cutting element removed therefrom and 50 with parts broken away to show details of the elevating mechanism.

Figure 3 is a transverse sectional view taken on line 3—3 of Figure 2.

Figure 4 is a detail showing the ratchet device for operating the elevating mechanism.

Figure 5 is an enlarged view of the cushion springs and associated parts of the elevating mechanism.

In the form in which my invention is embodied, as illustrated in the drawings, the cutting element 10 is mounted on a truck frame 11 having wheels 12, 12 preferably adapted for engagement with the track 13, 13. The cutting element may be of any suitable construction, including a kerf cutting device, draft device, and a motor for operating these devices. As herein shown, I prefer to use for the cutting element a short wall mining machine of a well known type, having as its main elements a forwardly projecting cutter arm 14 provided with a cutter chain, not shown, and with suitable winding drums indicated at 16. The motor, having suitable operative connections, is mounted in the casing 18 on the cutting element. Details of the motor and operative connections need not be described as they form no part of the present invention.

The standard cutting element 10 is carried at all times on the truck. While the machine is being transported from place to place the cutting element is arranged longitudinally of the truck body, as shown in Figures 1 and 2, and with its motor in operative connection with the truck wheels 12, 12 by means of a detachable driving connection of any suitable form. As shown herein, this connection includes a driving pin 15 detachably engaged in a socket member 26 to be driven by the mining machine motor. The pin 15 is operatively connected to the supporting wheels 12, 12 of the truck by any suitable mechanism, which may include a driving chain 27 and sprockets 32, 33, the latter sprocket being carried on the rear truck wheel. When cutting a kerf the cutting element is arranged to swing angularly about a fixed pivot on the truck frame. Details of the construction of the pivotal mounting for the cutting element are shown

in Figures 1 and 3. The base plate 19 of the cutting element rests upon and is secured to a plate 20 forming the turntable upon which the cutting element swings. A 5 stud 21 projects from the bottom surface of said plate and has pivotal bearing in a socket 22. This socket is secured to a longitudinally extending supporting plate 23. The pivotal stud 21 is preferably arranged substantially in alignment with the center of gravity of the cutting element 10 so that the latter will be substantially balanced on the supporting plate 23 while it is 10 swung thereabout. An annular bearing ring 24, herein comprising segmental sections 24^a, 24^b, is fixed to the supporting plate 23 concentric with the stud 21 to provide a bearing support for the turntable 20. The stud 21 may be secured in the journal 20 bearing 22 by means of the retaining plate 25 secured to said stud and extending laterally beyond the lower flange 22^a of said bearing.

25 The elevating mechanism includes a toggle device having as its principal elements two pairs 35, 35 and 35^a, 35^a, pivotally connecting the bed plate 23 in the truck frame 11 at the front and rear, respectively.

30 The front toggle members 35, 35 are connected to the supporting plate 23 by pivot pins 36, 36, and to the base plate 31 of the truck by pivot pins 37, 37. Similarly, the rear toggle members are connected to the supporting plate 23 and base plate 31 by pivot pins 36^a and 37^a, respectively. A pair 35 of longitudinally movable toggle members 38, 38 are adapted to coact with the toggle members 35, 35 and 35^a, 35^a, to raise the bed plate and cutting element as indicated 40 in dotted lines in Figure 1. Said toggle members are equal in length and the pairs thereof are arranged parallel with each other, so that the cutting element will be maintained in parallel relationship with the truck frame in all relative positions thereof. The toggle members 38, 38 are pivotally connected at their forward and upper ends to the bed plate 23, as for instance, on two pivot pins 29, 29, and at their lower and rear ends to a movable head 30 of a ratchet device, such as a lifting jack 39, lying horizontally of the base plate 31 and having its foot 40 engaging a stop 41 at the rear of the truck frame 11. Said ratchet device may 50 be of any approved pattern and may be secured in place by a clamp 42 attached to the truck frame 11. The arrangement is such that the entire bed plate 23, turntable 20 and cutting mechanism may be swung upwardly and forwardly about the pivotal members 35, 35 and 36, 36, by actuating the ratchet mechanism of the lifting jack 39. Details of the ratchet mechanism in the jack 39 are shown in Figure 4, as herein 60 shown comprising a standard form of jack

operating mechanism including a toothed rack member 43, a stationary pawl 44 and an operating pawl movably mounted on a lever arm 45. In the present instance I provide means for operating this lever arm 70 comprising a rod 46 pivotally connected to said arm at 47 and extending longitudinally to the rear end of the truck where it is pivotally connected to a lever arm 48 pivotally connected at 49 in an upright position where it may be manually manipulated by an operator standing at the rear end of the truck. In order to afford sufficient movement of the parts the rack member 43 is 75 made longer than is usual in ordinary jacks, herein extending through the foot 40 when the elevating mechanism is in its lowermost position as in Figure 1.

80 In order to provide the required rigidity of the elevating mechanism, I provide a plurality of guide plates 50, 50 secured in bearing engagement adjacent each of the toggle members 35, 35 and 35^a, 35^a. These bearing plates preferably are arranged in pairs 85 on both sides of each pivotal member, as shown, and extend a little short of half the length of the respective members, their outer margins 51 being curved on a radius, as 90 clearly shown in Figure 1. The arrangement is such that these guide plates provide a rigid lateral support for the toggle members 35, 35 and 35^a, 35^a, in all relative positions of the elevating mechanism.

95 In conjunction with the elevating mechanism I provide tension means for cushioning the downward movement and assisting the initial upward movement of the elevating mechanism. This means, in the present invention, is suspended below the base plate 31 of the truck frame 11 and between the 100 wheels 12, 12 thereof, so as to permit the elevating frame, and especially the relatively long pivotal bearing including the journal 22, to be lowered as far as possible and thereby afford a minimum overhead clearance 105 of the entire machine. As shown herein this tension means comprises a pair of springs 52, 52 housed in a casing 53 below the bed plate 31 of the truck frame 11, so as to be below the path of movement of the movable head 30 of the ratchet device 39. The rear ends of said springs are engaged 110 with a stationary stop 55 and the forward ends thereof engage a movable cross member 56. This cross member is connected with two parallel side bars 57, 57, movable longitudinally on opposite sides of the springs and turned upwardly at their rear ends to extend through the bed plate 31. A cross member 58 connects the rear upturned ends 115 of said plates and is arranged in position to engage a stop 59 (see Figure 1), formed on the movable head 30 of the ratchet device. The arrangement is such that the bars 57, 57 have a limited horizontal movement so 120 125 130

that the cross member 58 is engaged by the stop 59 on the movable head 30 only when the elevating mechanism is at or near its lowermost position. When said elevating 5 plate is in its lowermost position, as shown in full lines in Figures 1 and 2, the springs 52, 52 are placed under compression and tend to counteract the weight of the support and the cutting element thereon, there- 10 by providing a shock absorber to cushion the downward movement of the support res- 15 pective to the frame 11. The springs 52, 52 further assist in raising the support and cutting element from its lowermost position 20 when the toggle members 38, 38 are nearest their horizontal position and the maximum amount of horizontal pressure is required 25 from the jack in order to actuate the elevating mechanism. When the moving head 30 of the jack is actuated in raising the support, the cross arm 58 of arms 57, 57 moves there- 30 with until the limit of movement of said arms is reached, as for instance, as against a stop 60 on the base plate 31. Thereafter the cross arm 58 becomes disengaged from the moving head 30 but remains in position to be re-engaged thereby when the elevating support is again lowered.

It will be observed that additional sup- 35 port is provided for the turntable and cutting mechanism when in their lowermost position on the truck by the guide plates 50, 50, having bearing engagement with the toggle members 35^a, 35^a, and mounted on the bed plate 23 adjacent the pivotal point 36^a, and by the guide plates 50, 50, having bearing engagement with the toggle mem- 40 bers 35, 35, mounted on the bed plate ad- jacent the pivotal point 36, both pairs of 45 guide plates engaging the base plate 31 when the cutting mechanism has been lowered. Likewise the guide plates 50, 50, having bearing engagement with the toggle members 35^a, 35^a, and mounted on the base plate 31 adjacent the pivotal point 37^a, en- gages the bed plate 23 when the cutting mechanism is in its lowermost position.

Although I have shown and described one form in which my invention may be embodied, it will be understood that the construction and arrangement of the parts may be varied without departing from the spirit and scope of my invention. I do not, therefore, wish to be understood as limiting myself to the specific construction illustrated herein, excepting as specifically limited in the appended claims.

I claim as my invention:

1. In a mining apparatus, the combination of a truck element, a cutting mechanism, a support element therefor, means for elevating said support and cutting mechanism comprising a plurality of pivoted links, and guide means having lateral engagement with said links mounted on one of said ele-

ments and adapted to engage the other of said elements when the support and cutting mechanism is in its lowermost position.

2. In a mining apparatus, the combination of a wheeled truck, a cutting element, a support therefor, a centrally disposed pivotal mounting for said cutting element extending below said support, means for elevating said cutting element, and tension means beneath the body of the truck coact- 70 ing with the elevating means to retard the downward movement of the support and assist its initial upward movement. 75

3. In a mining apparatus, the combination of a wheeled truck, a cutting element, means 80 for elevating said cutting element, and a ratchet device operable from the rear end of said apparatus for actuating said elevating means.

4. In a mining apparatus, the combination of a truck element, a cutting mechanism, a support element therefor, means for elevating said support and cutting mechanism comprising a plurality of pivoted links, and arcuate guide means for said links having lateral engagement therewith adjacent the middle point thereof mounted on both of 90 said elements and adapted to engage the opposite element when the support and cutting mechanism is in its lowermost position. 95

5. In a mining apparatus, the combination of a wheeled truck, a cutting element, a support therefor, means for elevating said cutting element comprising a horizontally 100 movable rack member, and tension means comprising springs and a movable arm beneath the body of the truck coacting with the elevating means to retard the downward movement of the support and assist its initial upward movement. 105

6. In a mining apparatus, the combination of a wheeled truck, a cutting element, a support therefor, a depending pivotal mounting on said support for said cutting element, means for elevating said support and cutting element including a horizontally movable rack, and tension means movable parallel with but below the path of movement of 110 said rack whereby movement of said support is afforded to its lowermost position with its pivotal mounting disposed above said tension means. 115

7. In a mining apparatus, the combination of a wheeled truck, a cutting element, a support therefor, means for elevating said support including a horizontally movable rack, tension means coacting with said rack for a limited part of its movement to retard the downward movement of the support and assist its initial upward movement. 120

Signed at Chicago, in the county of Cook and State of Illinois this 5th day of November, 1923.

EDWARD J. DOBERSTEIN.
